JEAN BAPTISTE JOSEPH ALPHONSE VIGNERON, OF LA ROCHELLE, FRANCE, ASSIGNOR
TO V. D. LIMITED, OF LONDON, ENGLAND

TRAWLING GEAR

Application filed January 13, 1931, Serial No. 508,408, and in France January 13, 1930.

The invention relates to trawling gears, and more specially to trawling gears as disclosed in my prior specification No. 409,065, filed November 22, 1929, that is to fishing gears wherein the net has no belly nor foot rope, the rear pocket being provided with a rigid armature towed exclusively by traction cables to which are suspended weighted bands of net fabric adapted to seal the joint between the lower edges of the covering sheet and the ground.

One object of the invention is to replace the small rope at the entrance of the rear pocket by a rigid bar rotatably supporting a number of rollers adapted to readily ride over obstacles of the ground. I am aware of prior nets in which the ground rope is provided with rollers, but inasmuch as said rope is not rigid and assumes while fishing a catenary curved shape, the axes of the rollers, particularly the outer rollers, are strongly inclined to the perpendicular to the line of travel, so that such rollers are prevented from freely rotating and efficiently operating. Furthermore, the provision of a rigid bar for replacing the foot rope of usual nets was out of question, due to the great transverse length of the ground rope (some 10 to 20 metres) and experience has shown that a rigid bar of such length will be soon bent to an acute angle, although made very thick and strong. In the present net, the width of the entrance of the rear pocket is about 1 metre to 2 metres, and the rigid bar has been found to properly resist flexion.

In experiencing my new trawling gear, I also found that the weighted bands of netting suspended from the traction cables of the rear pocket are soon worn out through rubbing on the ground and I have found that bands of metal netting would properly resist and efficiently prevent the fish from escaping. It is another object of my invention to provide the net with such bands of metal netting.

In the accompanying drawings:

Fig. 1 is a plan view of my improved net.

Fig. 2 is a side view thereof.

Fig. 3 shows a detail of the curtain-like metal netting bands.

Referring to the drawings, 4 denotes the rear pocket of the net having at its entrance a rigid structure comprising a lower rigid bar 71, for example a steel tube, and vertical struts 76. Bar 71 has rotatably mounted thereon a number of rollers 72 and is attached to towing cables 8, the upper part of struts 76 being connected by inclined cables 77 to cables 8. 1 is a half-funnel shaped covering sheet attached to cables 8, whereby the net has no belly nor ground rope, the lower sheet of the rear pocket being bounded at the front by bar 71. Cables 8 are attached by a crow-foot 97 to a vertical slot 66, connected by the tow hawsers to the usual shear boards or the like (not shown).

From cables 8 are suspended bands of metal netting 78 adapted to rub on the ground and thus seal the joint between cables 8 and the ground. Such bands are preferably made (Fig. 3) of interlinked metal rings 103, like a coat of mail.

Besides its function of readily riding over obstacles and thus protecting the rear pocket from wear, bar 71 is useful in preventing entanglement of the various cables and steadies the whole structure. It also assists in the proper launching of the gear at sea, due to its weight. The attaching means for cables 8 preferably comprise a swivel. The lower sheet of the rear pocket may be attached at spaced points of bar 71, between the rollers, or it may be provided at the front with a rope located rearwardly of the bar and kept thereby at such distance from the ground that it cannot catch with obstacles.

Preferably, rings 103 are made of non-rusting metal or are lined with a suitable protecting coating. They may be provided with projections, hooks or points adapted to scratch the ground, raise clouds of mud and dig out the fish buried in the mud.

I wish to point out that the invention is not limited to any particular shape for the covering sheet and rear pocket. Thus, the latter may consist of a small ottertrawl net, with panels attached at the entrance, of a small VD net with stretching slats at the ends of the wings, of a small "boeuf net", formed of two lateral parts sewed along up-

per and lower middle cables, with stretching slats at the ends of the wings, etc.

Having now described my invention what I claim as new and desire to secure by Letters Patent is:

- 5 1. In a trawling gear, a net comprising a rear pocket, a rigid bar at the front lower edge thereof, rollers rotatably mounted on said bar, traction cables attached to said bar and a covering sheet attached to said cables.
- 10 2. In a trawling gear, a net comprising a rigid structure at the entrance of the rear pocket and embodying a lower rigid bar, rollers rotatably mounted on said bar, traction cables attached to said bar and a covering sheet attached to said cables.
- 15 3. In a trawling gear, a net comprising a rear pocket, traction cables for said rear pocket, a covering sheet attached to said cables and bands of metal netting suspended from said cables.
- 20 4. A trawling gear as claimed in claim 3, wherein said metal netting consists of inter-linked metal rings.
- 25 5. In a fishing net, a rigid bar, rollers rotatably mounted on said bar, a rear pocket adapted to be towed by said bar, traction cables attached to said bar, bands of netting suspended from said cables and a covering sheet extending forwardly of said rear pocket and attached to said traction cables.
- 30 6. In a fishing net, a small ottertrawl net forming the rear pocket, traction cables attached to the panels of said ottertrawl net, a covering sheet attached to said cables, and bands of netting suspended from said cables.

In testimony whereof I have signed my name to this specification.

JEAN BAPTISTE JOSEPH ALPHONSE VIGNERON.
